FIG.3.

UNITED STATES PATENT OFFICE

170,899

COMBINED POWDER BOX, LIPSTICK CONTAINER, AND HOLDER THEREFOR OR SIMILAR ARTICLE

Alice Jones Whitehead, New York, N. Y., and John Francis Lang, Clifton, N. J., assignors to Bourjois, Inc., New York, N. Y., a corporation of New York

Application June 22, 1953, Serial No. 25,608

Term of patent 14 years

(Cl. D58—26)

To all whom it may concern:

Be it known that we, Alice Jones Whitehead and John Francis Lang, citizens of the United States, residing at respectively, New York, New York, and Clifton, New Jersey, have invented a new, original, and ornamental Design for a Combined Powder Box, Lipstick Container, and Holder Therefor or Similar Article, of which the following is a specification, reference being had to the accompanying drawing, forming a part thereof.

Fig. 1 is a top plan view of a combined powder box, lipstick container, and holder therefor, showing our new design.

Fig. 2 is a side elevational view thereof.

Fig. 3 is a front elevational view thereof.

We claim:

The ornamental design for a combined powder box, lipstick container, and holder therefor, or similar article, substantially as shown.

ALICE JONES WHITEHEAD.
JOHN FRANCIS LANG.
